UNITED STATES PATENT OFFICE

2,605,908

DRAFT KEY RETAINER ADAPTER

Edward Payson Smith, Winnetka, Ill., assignor to
 Illinois Railway Equipment Company, Chicago,
 Ill., a corporation of Illinois

Application June 22, 1950, Serial No. 169,559

3 Claims. (Cl. 213—50.5)

1

My improved adaptor is more especially designed for use with an American Association of Railroads alternate standard draft key retainer, known as a fixed U or hairpin type, and is designed to overcome the weaknesses and difficulties encountered with this type of retainer.

The draft key retainer as heretofore employed consisted of a round bar formed into a U-shape with a straight intermediate horizontal portion terminating at the ends in vertical legs and forming a square U, with a small radius at the junctures between the horizontal intermediate portion and the two vertical legs; with the horizontal portion resting on the upper face of the key and the two vertical legs inserted or passing through two spaced holes in the draft key and the lower ends of the legs then bent laterally to hold the retainer in place.

The inherent weakness in this design exists at the sharp bends between the legs and the horizontal portion, which frequently resulted in fractures at said points.

The present improved A. A. R. retainer is designed to eliminate the sharp bends mentioned by providing a retainer having a large radius and provided with a round U-shaped bottom; while the leg receiving holes in the draft key have been countersunk to reduce the danger of fracture of the retainer. This change, however, introduced new points of wear on both the key and the retainer. While the former retainer was supported on the key by its horizontal portion, the later revised retainer is supported only at the two contact points of the semi-circular U-section of the retainer on the draft key, a condition which will cause excessive wear both on the key and the retainer.

My improved draft key adaptor for use with the rounded U-shaped retainer as hereinafter described is designed to eliminate the wear at the last mentioned points.

My improved adaptor is also designed to greatly decrease breakage of the retainer in service by transmitting the strains or load to both legs of the retainer; while at the same time eliminating interference between the retainer and the rivets on the center sill and obviating the necessity of counter sinking the retainer receiving holes in the draft key.

The objects and advantages of my invention will all be readily comprehended from the following detailed description of the accompanying drawings wherein:

Figure 1 is a plan view of one end of the draft

key with the key retainer and my improved adaptor applied.

Figure 2 is an end elevation of the structure as shown in Figure 1.

Figure 3 is a side view of the structure shown in Figure 2.

Figure 4 is a perspective view of my improved adaptor.

My improved adaptor is more especially intended for use with the American Association of Railroads altered standard draft key retainer 10 consisting of a bar of round cross-section and bent into U-shape with rounded bottom as shown at 11 in Figure 2, while the two legs 12, 12 extend through suitably spaced holes in the draft key, the tail end whereof is shown at 13, namely, the end which extends through and slightly beyond the center sill of which a portion is shown in section at 14, see Figures 1 and 3.

My improved adaptor 15, as more clearly shown in Figure 4, is of U-shape or clevis-like form with both sides identical in form to permit either side to be used at the top and thus eliminate the possibility of improper application.

The adaptor is a one piece forging consisting of the two similar wide end portions 16, 16; each provided with the spaced openings 17, adjacent opposite ends, which are adapted to register with the retainer receiving openings in the draft key 13. The two end or body portions 16, 16 are united by the narrower neck portion 18.

The body portions 16, 16 are each provided, intermediate the holes 17, with a vertically disposed lug or saddle portion 19, tapered somewhat toward the top which is slightly dished or arcuate from front to rear as shown at 20, see Figure 4. This lug 19, on the upper side of the adaptor constitutes a saddle or support for the intermediate arcuate portion 11 of the retainer 10, as more clearly seen in Figure 2. This support for the retainer eliminates the wear heretofore encountered at the holes in the draft key and also obviates the necessity for countersinking the holes in the draft key.

The marginal edges of the two body portions 16, 16 are each enlarged or formed with an elongated boss 21 which extends substantially throughout the full length of the body portion; and this boss preferably is formed with a sloping or arcuate vertically disposed surface which faces and at times may contact the adjacent side of the car center sill, see Figure 3; it being understood that the lower body portion 16 is similarly provided with an arcuate boss, thus making the adaptor reversible.

During car operation when the draft key is caused to move laterally with respect to the center sill, there is a possibility of interference between the draft key retainer and the rivets on the center sill which would result in undesirable strains on the retainer; and at times a large shearing force on one leg of the retainer is exerted, as when the car is going around a curve and the retainer is forced against the center sill.

With my improved adaptor and its horizontally extending boss at the forward center sill facing edge, the retainer is prevented from contact with the center sill rivets; and with the forward bearing oppositely sloping or arcuate surface, of predetermined degree, the shearing force will always be transmitted to both legs of the retainer.

In practice, the adaptor is first applied to the apertured tail end of the draft key, as shown in Figure 3, with its holes 17, 17 brought to register with the holes in the draft key. The retainer 10 is then applied by inserting its two legs through the holes 17 in the adaptor and those in the draft key and the curved upper end of the retainer allowed to rest on the saddle 19. The lower protruding ends of the legs 12, 12 of the retainer are then preferably bent laterally as shown in Figure 2 to hold the retainer against accidental removal.

The exemplification shown and described is believed to be the best embodiment of my invention, but structural modifications may be possible without, however, departing from the spirit of my invention as defined in the appended claims.

What I claim is:

1. A draft key retainer adaptor comprising, in combination with a railroad car center sill, a draft key extending through the center sill and provided with openings and a key retainer disposed through the key openings; a clevis-like adaptor adapted to endwisely receive the apertured end of the draft key and provided with two plate-like portions apertured to register with the draft key openings, for passage of the key retainer therethrough, the outer surfaces of the plate-like portions, intermediate the apertures being provided with raised retainer supporting portions.

2. A draft key retainer adaptor comprising, in combination with a railroad car center sill, a draft key extending through the center sill with its tail end provided with a pair of spaced holes and an inverted U-shaped key retainer adapted to extend through the holes in the draft key; a clevis-like adaptor with a pair of similar plate-like portions adapted to endwisely fit onto the tail end of the draft key and each portion having a pair of holes arranged to register with the holes in the draft key and adapted to receive the legs of the key retainer, the outer surfaces of said plate-like portions being provided intermediate the holes with saddle portions for supporting the intermediate curved portion of the key retainer.

3. In combination with a railroad car draft key whose tail end is provided with transversely spaced holes and a U-shaped retainer whose legs are adapted to fit into the draft key holes; a reversible adaptor of clevis-like form with similar plate-like ends both laterally enlarged and arranged to extend flush with the upper and lower faces of the draft key having spaced holes adapted to register with the holes in the draft key and united by a neck portion adapted to extend about the end of the draft key, both of said plate-like ends intermediate the holes having vertically disposed tapering retainer supporting portions disposed from end to end, while the forward edges of said plate-like ends are provided with enlarged arcuate center sill contacting surfaces, to distribute the load to both legs of the retainer.

EDWARD PAYSON SMITH.
